UNITED STATES PATENT OFFICE

ZEBULON HUNT, OF HUDSON, NEW YORK.

IMPROVEMENT IN COOKING-STOVES.

Specification forming part of Letters Patent No. 147,500, dated February 17, 1874; application filed December 20, 1873.

To all whom it may concern:

Be it known that I, ZEBULON HUNT, of the city of Hudson, in the State of New York, have invented an Improvement in the Bottom Flue of a Cooking-Stove, of which the following is a specification:

The object of my invention is to more perfectly equalize and distribute the heat on the bottom of the oven of a cooking-stove, by causing the hot-air, &c., to circulate along the outer edges or sides of the bottom flue, and eddies of heat to distribute themselves all over the middle and other portions of the bottom not in the track of the unobstructed circular current.

This I effect by elevating the middle of the bottom of the stove into a longitudinal double-inclined or roof-formed ridge, (see Fig. 2,) of such height as, with a ridge-piece, known as a flue-strip, of about an inch in width, to form a close partition. The two ends of this elevation are inclined like the sides. The front end of the flue, or that nearest the ash-pit, is open and unobstructed, so that the hot air may pass freely around from one side to the other, and the back or rear end is divided by the back partition *d* extending to the bottom of the flue and up this inclined end, as shown in Fig. 1, until it meets the before-mentioned ridge-piece, so as to entirely separate the ascending and descending currents of hot air, &c., as shown by the darts in the same figure. And, further, by erecting on the two sides of this double-inclined partition *I* perpendicular wings or deflectors *c c c e*, three of which may be seen in the perspective view, Fig. 1, standing at angles with the middle line or ridge piece of about forty-five degrees in front, and reaching vertically from the inclines to the bottom of the oven. As said above,

Figure 1 is a perspective view looking into the rear end of the stove, the lower portion of the back plate removed for that purpose, exhibiting the interior construction. Fig. 2 is a plan view of the bottom of the stove, showing the double incline or roof-formed elevation *I*, and the location and angle of the wings or deflectors by the wing-ribs *c c c e* and stops represented thereon; and Fig. 3 is a plan view of the under or flue side of the bottom plate of the oven.

The darts on Figs. 1 and 2 of the accompanying drawings indicate the course of the current of hot-air, &c.; the curved darts the eddies caused by the wings or deflectors *c c c e*.

I employ two pairs of these wings, one pair on each side of the double incline *I*, but do not wish to confine myself to any definite number, intending to use more or less of them, as I find most advantageous.

This arrangement produces what I call a circular-draft cooking-stove. It differs from the ordinary so-called two-flued cooking-stove, not only in construction, but in its operation and results. Ordinarily, the bottom partition is a single vertical plate without wings, and when the hot air comes down the back flue it hugs this middle partition on both sides and leaves the outer sides of the bottom flue only partially heated, while the middle of the oven bottom next to the partition is heated to excess. In my improvement this is obviated, and the heat is equalized and evenly distributed on the entire bottom of the oven. The wings or deflectors *c c*, &c., throw the hot air, &c., current out to the outer sides of the flue, (see Fig. 2,) while sufficient separates from it and revolves in eddies around these wings, and up to the middle and other parts of the bottom not in the circular current. The dust and ashes which fall upon the sides of this double incline slide down into the main flue, and are thence easily drawn out through the flue-stops *P P* into the ash-pits in front. The upright partition *d* divides the back-flue into two parts, one for the descending and the other for the ascending hot air, &c., and meets the bottom ridge-piece, and runs thence down the inclined rear end of the ridge-partition *I* to the bottom plate, so as effectually to separate the two currents. The effect of the wings *c c*, &c., is to check and divert a portion of the current of hot air, &c., and prevent it passing off so rapidly into the smoke-pipe, while it does not injure the draft of the stove, the main passage being unobstructed and the main circular current unimpeded. The outer and wider ends of these wings *c c*, &c., stand forward of the inner and narrower ends, forming an angle with the middle line or flue-strip of about forty-five degrees, and extend vertically from the inclines up to the bottom of the oven. These

wings or deflectors *c c*, &c., may be used in the bottom flue of a cooking-stove, in connection with a single upright central partition, instead of the double inclined, and produce in a degree the same or similar results. This roof-formed elevation I is usually formed and cast in the bottom plate, or it may be built upon it.

I claim—

The double-inclined elevation I, provided

with the wings or deflectors *c c c c*, in combination with the bottom-flue of a cooking-stove, substantially as and for the purposes herein described.

ZEBULON HUNT.
